Primary Examiner — Jonathan J Han(74) *Attorney, Agent, or Firm* — Hartman Global IP Law; Gary M. Hartman; Domenica N.S. Hartman(57) **CLAIM**

The ornamental design for a footwear as shown and described.

DESCRIPTION

FIG. 1 is a top front perspective view of a footwear showing my new design;

FIG. 2 is a bottom rear perspective view thereof;

FIG. 3 is a right elevation view thereof;

FIG. 4 is a left elevation view thereof;

FIG. 5 is a front elevation view thereof;

FIG. 6 is a rear elevation view thereof;

FIG. 7 is a top plan view thereof; and,

FIG. 8 is a bottom plan view thereof.

The evenly-spaced broken lines in FIGS. 1 through 8 illustrate stitching of the footwear and form part of the claimed design.

1 Claim, 8 Drawing Sheets(56)
